CIGAR AND MOUTHPIECE THEREFOR

Milton Wertheimer, Baltimore, Md.

Application August 16, 1938, Serial No. 225,185

8 Claims. (Cl. 131—52)

This invention relates to improvements in cigars and particularly in the mouth piece thereof and its method of attachment to the cigar.

The tip is preferably made of one of the plastic materials which may be either a thermoplastic or one of the molded plastics. The tip presents to the mouth of the user a smooth almost glass like surface and yet it is so thin that it may be bit by the teeth for holding with comparatively little danger of perforation since although it is rigid it is likewise somewhat soft and resilient because of the oval or elliptical shape of the end portion intended to be inserted in the mouth.

The mouth piece is composed of a cylindrical portion into which the filler of the cigar is placed and this cylindrical portion has a shoulder adjacent its extremity around which the wrapper that surrounds the cigar is placed so that the tip and cigar are made up as a unit. Projecting from this cylindrical portion of the mouth piece is an oval or elliptical piece intended to be grasped between the lips and teeth of the user and since the material is so thin and flexible and yet hard, in order to reenforce it for use, it is ribbed internally and these ribs extend longitudinally to prevent the closing of the passage in the oval or elliptical portion when the oval portion is partially collapsed between the teeth of the user. These ribs insure passage of the smoke through the tip at all times. The extreme end of the oval or elliptical portion is reenforced or thickened integral with both the oval or elliptical portion and the ribs, and the end of the mouth piece is smooth and presents a large flat edge to the tongue of the user and it has therein a rectangular slot through which the smoke is drawn. This reenforcing of the extreme end and the cylindrical portion insures a firm externally smooth mouth piece which will not collapse either lengthwise or at its tip in actual use. Also the reenforcement at the extreme end of the piece will prevent particles of the cigar from being drawn through the mouth piece into the mouth.

The above and other advantages which will be apparent hereinafter are accomplished by the cigar and mouth piece described in the accompanying drawing forming a part hereof and in which:

Figure 1 is a view of a cigar with the mouth piece attached.

Figure 2 is a partial sectional view thereof on line 2—2 of Fig. 1.

Figure 3 is an enlarged view of the mouth piece.

Figure 4 is a sectional view on line 4—4 of

Fig. 3 and also showing in section a part of the cigar.

Figure 5 is an end view of the mouth piece from the direction of the oval or elliptical portion.

Figure 6 is an end view of the mouth piece from the direction of the cylindrical portion.

In the drawing similar numerals refer to similar parts throughout the views.

The mouth piece 1 has a cylindrical portion 2 into which is inserted the filler 3 of a cigar. A wrapper 4 of the cigar is placed around the filler and around the cylindrical portion 2 of the mouth piece and the mouth piece has a shoulder 5 larger than the cylindrical portion 2 so as to make a continuous surface between the mouth piece and the wrapper 4, as shown in Figs. 1, 2 and 4. The mouth piece has integral with this cylindrical portion an oval or elliptical portion 6 which the user may firmly grasp between his lips and teeth. This oval or elliptical portion is reenforced or thickened internally as shown at 7 and this portion 7 preferably presents substantially a right angle internally to the oval or elliptical portion so that particles of tobacco will not be drawn through the rectangular opening 8 in the end of the mouth piece. The reenforced or thickened portion 7 of the oval or elliptical portion of the mouth piece is flat and presents a plane surface to the tongue and lips of the user and the small rectangular opening 8 is so small as to prevent the tongue from being pushed into the mouth piece and therefore to prevent the tongue from being cut or bruised, and not only does it prevent this cutting but it presents a flat smooth surface to the tongue which is very pleasing to the user. Longitudinally extending ridges 9 also reenforce the oval or elliptical portion of the mouth piece so that on the partial collapse of the mouth piece the ridges will insure that smoke will pass from the cigar to the user.

It will be apparent from the above description that a very thin mouth piece may be constructed that will be very economical in manufacture, and in the use of material and which will present a smooth surface to the mouth of the user and which will allow those desiring to chew it, as is often done with the end of a cigar, and yet prevent the complete collapse of the end of the tip so that the smoke may be constantly drawn through and the smoothness of the material not be in any way injured in actual use.

While one embodiment of the invention has been shown and described it is to be expressly understood that the showing and description are

for purposes of illustration only and are not designed as a definition of the limits of the invention for which references should be made to the appended claims.

5. By substantially elliptical, as used in the claims, is meant a geometrical form which has substantially the curve characteristic of a true ellipse except that the curve at the ends of the major axis closely approximate the formation of an acute angle with straight sides.

10. What is claimed is:

1. A mouthpiece for cigars and the like made of thin, hard, plastic material comprising a substantially cylindrical portion for attachment to a cigar, a substantially elliptical and flattened mouth portion terminating in a slotted end, the wall of said mouth portion being transversely thickened at said slotted end, and internally projecting means on one interior wall thereof between the longitudinal edges of the mouth portion and spaced from the opposed wall thereof, to prevent its closing by biting with normal use.

2. A mouthpiece for cigars and the like made of thin, hard, plastic material comprising a substantially cylindrical portion for attachment to a cigar, a substantially elliptical and flattened mouth portion terminating in a slotted end, said elliptical mouth portion being resilient to permit it to yield to biting and having on its interior surface means projecting from one interior wall thereof, and spaced from the opposite wall thereof and being positioned intermediate the longitudinal edges thereof to prevent its closing by biting with normal use.

3. A mouthpiece for cigars and the like made of thin, hard, plastic material comprising a substantially cylindrical portion for attachment to a cigar, a substantially elliptical and flattened mouth portion terminating in a slotted end, said elliptical mouth portion being resilient to permit it to yield to biting and having on its interior surface longitudinal ridges projecting therefrom, and a ridge on one surface thereof being spaced from a ridge on an opposite surface thereof and being positioned intermediate the longitudinal edges thereof to prevent its closing by biting with normal use.

4. A mouthpiece for cigars and the like made of thin, hard, plastic material comprising a substantially cylindrical portion for attachment to a cigar, a substantially elliptical and flattened mouth portion terminating in a slotted end, said elliptical mouth portion being resilient to permit it to yield to biting and having on its interior surface a plurality of means, one opposite to another and spaced therefrom and being positioned intermediate the longitudinal edges thereof to prevent its closing by biting with normal use.

5. A mouthpiece for cigars and the like made of thin, hard, plastic material comprising a substantially cylindrical portion for attachment to a cigar, a substantially elliptical and flattened mouth portion terminating in a slotted end, the wall of said mouth portion being transversely thickened at said slotted end and longitudinal ridges projecting from the interior surface of said mouth portion and a ridge on one portion of said surface being spaced from a ridge on an opposite portion thereof and being positioned intermediate the longitudinal edges thereof, said mouth portion being resilient to permit it to yield to biting and being limited in its resiliency by the relatively rigid cylindrical portion and the thickened slotted end and prevented from closing thereby and by said ridge or ridges, by biting with normal use.

6. A mouthpiece for cigars and the like made of thin, hard, plastic material comprising a substantially cylindrical portion for attachment to a cigar, a substantially elliptical and flattened mouth portion terminating in a slotted end, the wall of said mouth portion being transversely thickened at said slotted end and longitudinal ridges projecting from the interior surface of said mouth portion and one ridge on one portion of the surface being spaced from the opposite portion thereof and being positioned intermediate the longitudinal edges thereof, and joining integrally with said thickened slotted end.

7. A mouthpiece for cigars and the like made of thin, hard, plastic material comprising a substantially cylindrical portion for attachment to a cigar, a substantially elliptical and flattened mouth portion terminating in a slotted end, the wall of said mouth portion being transversely thickened at said slotted end and internal spaced projections positioned intermediate the longitudinal edges of said mouth portion, said mouth portion being resilient to permit it to yield to biting and being limited in its resiliency by the relatively rigid cylindrical portion and the thickened slotted end and prevented from closing thereby and by said internal projections, by biting, with normal use.

8. A mouthpiece for a smoking article formed of plastic material and comprising a substantially cylindrical portion at one end merging into an intermediate narrow portion of oval cross section and tapering gradually toward the opposite end, the latter end having an internal transverse reinforcement and the tapered portion being thin and resilient and having internal spaced projections whereby to prevent its closing by biting with normal use.

MILTON WERTHEIMER.
